Primary Examiner — Sandra Snapp*Assistant Examiner* — Leisha Price(74) *Attorney, Agent, or Firm* — Quickpatents, LLC;
Kevin Prince(57) **CLAIM**

The ornamental design for a lug nut bolt, as shown and described.

DESCRIPTION

FIG. 1 illustrates a front view of the lug nut bolt showing our new design with the rear elevation views being a mirror image thereof;

FIG. 2 is a bottom perspective view thereof;

FIG. 3 is an alternate bottom perspective view thereof;

FIG. 4 is a top perspective view thereof; and,

FIG. 5 is an alternate top perspective view thereof.

1 Claim, 3 Drawing Sheets(56)
